DISPLAY BOX FOR WATCHES AND THE LIKE

Alan B. Lowry, Canton, Mass., assignor to Farrington Manufacturing Company, Needham Heights, Mass., a corporation of Massachusetts

Application March 7, 1958, Serial No. 49,937

Term of patent 7 years

(Cl. D80—5)

Fig. 1 is a perspective view of a display box for watches and the like showing my new design;

Fig. 2 is a side elevational view thereof;

Fig. 3 is a plan view of the display box looking in the direction of the right hand arrow of Fig. 2;

Fig. 4 is a front elevational view of Fig. 2 looking in the direction of the left hand arrow shown in Fig. 2; and

Fig. 5 is a perspective view similar to that shown in Fig. 1 but with a portion of the box rotated to open position.

I claim:

The ornamental design for a display box for watches and the like, as shown.
